UNITED STATES PATENT OFFICE.

IDA ST. JOHN OYE, OF WHITE PLAINS, NEW YORK.

SPRAY APPARATUS FOR TREATING FOOT AILMENTS.

Application filed March 6, 1926. Serial No. 92,757.

My invention relates to an apparatus for treating foot ailments and more particularly to a foot spraying receptacle in which the patient's feet are placed above and in front 5 of a plurality of spray pipes constructed to project the spray solely upon the parts of the feet being treated.

One of the objects of the invention is to provide a foot spraying apparatus which can 10 be used for the treatment of abnormal conditions of the nerves and muscles of the feet and to assist in the treatment for readjustment of the bones, ligaments and tendons of the feet in cases of weakened longitudinal arches, flattened transverse arches, shortened 15 Achilles tendons and all cases of pain and strain of the feet and ankles.

With the above and other objects in view, my invention consists in the parts, improvements and combinations hereinafter described.

Referring to the drawings which illustrate one embodiment of the invention:

Figure 1 is a top plan view of the foot spraying receptacle.

Figure 2, is a vertical transverse section on line 2—2 of Figure 1,

Figure 3, is a vertical transverse section on line 3—3 of Figure 2, the plane of section 30 being at right angles to that of Figure 3, and

Figure 4, is a top plan view of the cover, showing the foot openings and cuffs for the legs, to prevent escape of water.

In accordance with the invention, I provide 35 a foot receptacle having walls 1, preferably of porcelain, the exterior of which may be square and the interior cylindrical, with a flat bottom rounded at the edge, as illustrated.

A foot spray comprising a plurality of 40 spray pipes 2, 3, 4, is arranged at the bottom of the receptacle and preferably embedded in the porcelain bottom wall. The spray holes in these pipes are arranged to project the spray only upon the parts of the soles of the 45 feet being treated, and so as not to flood the entire foot with water. Pipe 4, sprays the heel of the foot and pipes 2 and 3, spray portions of the sole of the foot, pipe 2, being arranged under the toes and pipe 3, under the 50 beginning of the arch of the foot.

Two longitudinal cross spray pipes 5, 6, one 55 for each foot, extend between the two sole spray pipes and run lengthwise of the feet thus spraying the foot arches. A foot spray is thus provided for the sole of each foot, including a separate toe spray, which sprays the ball

of the foot adjacent to the toes, a separate heel spray, and a separate arch spray, the toe spray pipe being transverse to the arch spray pipe. By this means different portions of the 60 feet can be simultaneously sprayed. A curved spray pipe 7, extends around the back of the receptacle and is provided with spray openings at the portions 8 and 9, so as to spray the backs of the ankles of the two feet when 65 treating pain or strain in the Achilles tendons.

Hot and cold water may be supplied to the spray pipes by a mixing pipe (not shown) from which the water passes into supply pipe 70 10. From the supply pipe water passes into spray pipes 2, 3, 4 and 7, then branch pipes 11, 12, 13 and 14, located in the walls of the receptacle, each of which is respectively controlled by a valve 15, 16, 17, 18. The spray 75 stimulates the separate parts of the feet through impact of the jets of water. The person using the spray sits so that the feet hang in the receptacle without resting on any surface, the receptacle being open to the atmosphere. The feet are placed about four 80 inches away from the spray openings, thus making the stimulation from the beat of the jets of water, pleasant and beneficial.

A cover 19, is provided for the receptacle 85 with foot holes 20, 21, thru which the feet of the person using the spray can be inserted. Water-tight cuffs 22, 23, are provided which the legs fit and which prevent escape of water 90 outside the receptacle.

The water runs off by means of waste pipe 24.

Having thus described the invention, it will be understood that changes may be made in the form, construction and arrangement of 95 the spray pipes and receptacle without departing from the principle of the invention.

What I claim is:

1. An apparatus for treating foot ailments comprising a foot receptacle, a foot spray 100 provided with two longitudinal spray pipes one for each foot arranged at the bottom of the receptacle above which pipes the soles of the feet are respectively adapted to rest, each of said pipes extending lengthwise below the 105 arch of the foot, the spray from the pipe projecting solely upon the parts of the soles being treated.

2. An apparatus for treating foot ailments comprising, a foot receptacle, a cover with 110 two foot openings, fitting the top of said receptacle, a plurality of separated spray pipes

arranged at the bottom of the receptacle above and at a distance from which the plan-
tar surfaces of the feet are adapted to rest,
two of said pipes supplying the soles and one
5 the heels of the feet, and two longitudinal
spray pipes each extending lengthwise of the
sole and below the arch of the foot, each lon-
gitudinal arch pipe provided with spray
openings extending along the length of the
10 pipe, the said arch spray pipes and two of
said sole spray pipes being transversely con-
nected.

3. An apparatus for treating foot ailments
comprising, a foot receptacle, a foot spray
15 provided with a longitudinal spray pipe ar-
ranged at the bottom of the receptacle above
which pipe the sole of the foot is adapted to
rest, the said pipe extending lengthwise be-
low the arch of the foot, the spray from the
20 pipe projecting solely upon the parts of the
sole being treated, and a curved spray pipe
adapted to surround and spray the backs of
the ankles of the two feet.

4. An apparatus for treating foot ailments
comprising a foot receptacle open to the at-
mosphere and adapted to receive the two feet
of the patient, a cover with two foot open-
ings, fitting the top of said receptacle, a foot
spray for the two feet, provided with a plu-
rality of separated spray pipes arranged at
the bottom of the receptacle above and at a
distance from which pipes the soles of the two
feet are adapted to rest, said foot spray in-
cluding a toe spray pipe and a heel spray
35 pipe extending across and below the toes for
spraying the bottoms of the toes for each foot,
so as to simultaneously spray different por-
tions of the feet, the spray from the pipes pro-
jecting solely upon the parts of the feet be-
ing treated, a supply pipe connected with the
40 spray pipes for supplying hot and cold water
to the spray pipes, and a waste pipe for dis-
charging the water from the receptacle.

In testimony whereof, I have signed my
name to this specification.

IDA ST. JOHN OYE.
